[57] ABSTRACT

Accommodated in the housing of the runner are levers of the rotatable blades, a cross-piece and a servomotor provided with a winged piston. The levers are fixed to the journals of the rotatable blades. With the cross-piece being arranged above the journals of the rotatable blades and pivotally connected to the levers. The blades are rotated by means of the servomotor having the winged piston which is provided with rotatable and fixed wings. The rotatable wings of the servomotor are rigidly fixed to the cross-piece.

The invention can be advantageously used in the runners of Kaplan and Deriaz water turbines and in turbine-pump units of high capacity.

RUNNER OF HYDRAULIC MACHINE HAVING ROTATABLE BLADES

BACKGROUND OF THE INVENTION

The present invention relates to hydraulic machines and more specifically to a runner of a hydraulic machine having rotatable blades.

The invention can be most advantageously applied to the runners of Kaplan and Deriaz water turbines, as well as in high performance hydraulic pumps.

PRIOR ART

In a prior art runner, e.g., a Deriaz water turbine, accommodated in the housing of the runner are levers fixed to the journals of rotatable blades. The blades are rotated by means of a hydraulic servomotor having a winged piston via an intermediate shaft and a cross-piece. The cross-piece is pivotally connected to the levers of the rotatable blades. The pivot connection between the cross-piece and the levers is provided by means of spherical pins with a spherical head and floating slide blocks accommodated in the slots of the cross-piece. The cross-piece and blade rotating means are arranged under the journals of the rotatable blades. The levers of the rotatable blades, the pins with a spherical head and the floating slide blocks are referred to hereinbelow. An important hydraulic torque is applied to the blades of the runner, with the force induced by this torque being transmitted to the cross-piece and the intermediate shaft. This force gives rise to a great bending moment in the cross-piece, thereby resulting in a high bending stress in the walls of the slots thereof, as well as to a high torque in the intermediate shaft with a corresponding high torsional stress therein, which, in turn, results in considerable oversizing of these parts in high capacity machines taking into account the required strength of the cross-piece and the intermediate shaft.

The use of the intermediate shaft and disposition of the cross-piece and blade rotating means under the journals of the rotatable blades do not make it possible to reduce the dimensions of the runner housing, which is necessary for the runners of Deriaz water turbines operating under a high head or for high capacity hydraulic pumps, and causes difficulties during their transportation.

Furthermore, it is known to accommodate in the runner of e.g., a Deriaz water turbine, levers which are fixed to the journals of rotatable blades. The rotatable blades are rotated by means of a piston servomotor. Translatory motion of the piston through a rod, cross-piece, link and the lever causes the rotation of the blades.

This runner is also heavy and difficult to manufacture.

OBJECTS AND SUMMARY OF THE INVENTION

It is an object of the present invention to increase the efficiency of the runner.

Another object of the invention is to improve the cavitation characteristics of the runner.

Still another object of the invention is to provide simpler structure for the runner.

The above and other important objects are accomplished in that in a runner of a hydraulic machine having rotatable blades, comprising a housing accommo-

dating a cross-piece pivotally connected to levers which are fixed to the journals of the rotatable blades and actuated by means of a servomotor having a winged piston, according to the invention, the rotatable blades of the winged piston of the servomotor are rigidly fixed to the cross-piece.

This runner is simpler in design and lighter in weight.

It is advantageous to arrange the cross-piece accommodated in the runner housing above the journals of the rotatable blades. This makes it possible to reduce the runner housing size and to facilitate its transportability, which is particularly important for high capacity Deriaz water turbines, and to reduce the diameter at the intersection of the axis of the blade rotation with the outer profile of the runner housing, whereby the cavitation characteristics of the runner are improved.

A Deriaz water turbine having rotatable blades designed for a head of 100 m and with 220,000 kw output, which is provided with the runner according to the invention, has the efficiency increased by 3 percent and the cavitation factor reduced by 0.09.

Other objects and advantages of the present invention will become more apparent from the following examples of the embodiment thereof given with reference to the accompanying drawings, in which:

BRIEF DESCRIPTION OF THE DRAWINGS

FIG. 1 schematically shows a runner according to the invention, in longitudinal section;

FIG. 2 is a sectional view taken along the line II-II in FIG. 1, the view looking in the direction of the arrows;

FIG. 3 shows another embodiment of the runner according to the invention, in longitudinal section;

FIG. 4 is a sectional view taken along the line IV-IV in FIG. 3, the view looking in the direction of the arrows.

DETAILED DESCRIPTION OF THE EMBODIMENT

A runner of a Deriaz water turbine comprises a housing 1 (FIGS. 1, 3) accommodating levers 2 of rotatable blades 3, a cross-piece 4 and a servomotor 5 having a winged piston.

The levers 2 are fixed to journals 6 of the rotatable blades 3. The cross-piece 4 is mounted above the journals 6 of the rotatable blades 3 and is pivotally connected to the levers 2. One end of a pin 7 is fixed to the cross-piece 4, while the other end of the pin, which is provided with a spherical head 8, engages a floating slide block 9. Each lever 2 is provided with a slot 10 extending at a right angle with respect to the axis of the pin 7 with the spherical head 8, and the floating slide-block 9 being accommodated in this slot 10. The blades 3 are rotated by means of the servomotor 5 having a winged piston, and rotatable wings 11 (FIGS. 1, 2) of this piston are rigidly fixed to the cross-piece 4 (FIG. 1) by means of bolts 12, while fixed wings 13 (FIGS. 1, 2) are attached to a stationary disc 14 (FIG. 1). Mounted within a hollow shaft of the turbine (not shown in the drawings) are hollow rods 15 adapted to supply oil into the servomotor 5 and a central pipe 16 adapted to supply air under the runner in order to improve its cavitation characteristics.

In another embodiment of the runner, the axis of the pin 7a with the spherical head 8a (FIG. 3) extends in parallel to the axis of rotation of the blades 3, thereby making it possible to provide for removal of a cylinder 17 of the servomotor 5a provided with a winged piston. The cylinder 17 is rigidly fixed to the runner housing 1a by means of bolts. The fixed wings 13a (FIG. 4) are attached to the cylinder 17 of the servomotor 5a.

The runner is simple in design and smaller in size.

We claim:

1. A runner of a hydraulic machine having rotatable blades, comprising a runner housing; journals for said rotatable blades; a cross-piece accommodated in said

housing above the journals for the rotatable blades; levers disposed in said housing; said levers being fixed to the journals of said rotatable blades and pivotally connected to said cross-piece; a servomotor for rotating said blades, said servomotor being provided with a winged piston having rotatable and fixed wings, and means fixing said rotatable wings rigidly to said cross-piece.

2. The runner of a hydraulic machine having rotatable blades according to claim 1, further including a stationary disc within the housing above the cross-piece to which the fixed wings are attached.
